UNITED STATES PATENT OFFICE.

WILLIAM KOWALSKI, OF BROOKLYN, AND GEORGE A. GUNTHER, OF BATH,
NEW YORK, AND ISAAC S. McGIEHAN, OF LAFAYETTE, NEW JERSEY.

SPARK-ARRESTER.

SPECIFICATION forming part of Letters Patent No. 247,256, dated September 20, 1881.

Application filed February 28, 1881. (No model.)

To all whom it may concern:

Be it known that we, WILLIAM KOWALSKI, residing at Brooklyn, in the county of Kings, State of New York, GEORGE A. GUNTHER, residing at Bath, Long Island, New York, and ISAAC S. McGIEHAN, residing at Lafayette, county of Hudson, State of New Jersey, have invented a new and useful Improvement in Spark-Arresters for Locomotives, by which sparks can be arrested and the draft regulated, of which the following is a specification.

The object of our invention is to find means by which sparks from the boiler of a locomotive may be prevented from reaching the air through the smoke-stack and at the same time to accomplish this result to impair in no manner the force of the draft, but by some contrivance so to regulate it that it can be increased or diminished at the option of the engineer.

Reference being had to the drawings, Figure 1 is a central vertical longitudinal section of a locomotive on line *x x*. Fig. 2 is a central vertical transverse section on line *y y*. Fig. 3 is a section on the line *z z*.

Similar letters refer to similar parts throughout the drawings.

A is a diaphragm-sheet or deflecting-plate, which is placed in a vertical position, and is 30 parallel with the front tube-sheet, (indicated by H.)

B is a platform of sheet-iron, which extends from the tube-sheet above the top of the tubes to within one-third of the distance from the 35 tube-sheet to the front of the extended smoke-box K. In the platform B are two slots, F F, by means of which the deflecting-plate A may be either moved backward or forward, so as to increase or decrease the distance between 40 it and the tube-sheet.

G is the exhaust-nozzle, which passes through the platform B.

Extending to the top of the fire-box, at an angle of sixty degrees, is a wire-netting, (indicated by C,) which arrests all sparks that may 45 have retained velocity sufficient to have carried them there.

In the base of the stack are openings D D, whereby air may be admitted in a sufficient quantity to retard the velocity of the exhaust- 50 steam, and thereby deaden the noise caused by the said exhaust.

E is a movable joint that may be moved up and down in the stack, by which the openings may be partly or entirely closed or opened, 55 thereby regulating the draft.

H is the front tube-sheet.

The operation is as follows: After the sparks have left the tubes they go in the direction indicated by the arrows in Fig. 1, and, after striking the deflecting-plate A, are thrown downward, to be carried again to the platform B, against which they will strike and fall to the front end of the extended smoke-box K.

What we claim, and desire to secure by Letters Patent, is—

1. In a locomotive smoke-stack, the combination of a movable deflecting-sheet, A, attached to a platform of sheet-iron, B, and connected with a wire-net, C, constructed and arranged 70 as hereinbefore set forth and described.

2. In a locomotive smoke-stack, the combination of the movable deflecting-sheet A, the wire net C, and platform B, with a smoke-stack having at its base a movable joint, E, and the 75 openings D, as and for the purposes described.

WILLIAM KOWALSKI.
GEO. A. GUNTHER.
ISAAC S. McGIEHAN.

STEPHEN PFEIL.

Corrections in Letters Patent No. 247,256.

It is hereby certified that in Letters Patent No. 247,256, issued September 20, 1881, to William Kowalski, of Brooklyn, N. Y., George A. Gunther, of Bath, New York, and Isaac S. McGiehan, of Lafayette, New Jersey, for an improvement in "Spark-Arresters," errors occur in lines 16 and 67 of the printed specification forming a part of said Letters Patent requiring correction, as follows: in line 16 for "to accomplish" read "in accomplishing;" in line 67 strike out the word "smoke-stack;" that the proper corrections have been made in the files and records of the Patent Office and are hereby made in said Letters Patent.

Signed, countersigned, and sealed this 11th day of October, A. D. 1881.

[SEAL.]

A. BELL,
Acting Secretary of the Interior.

Countersigned:

E. M. MARBLE,
Commissioner of Patents.
